GELES, CALIFORNIA, A CORPORATION OF CALIFORNIA

DIAPHRAGM HEAD FOR PUNCTURING CLOSURE DISKS

Application filed January 30, 1929. Serial No. 336,155.

This invention relates to a device for puncturing the closure member of a fluid container so that the fluid is released. In this application for Letters Patent we show a preferred form of the invention, it being understood that we realize that different changes may be made in a device like this without departing from the principle involved; therefore, we intend the scope of this invention to be construed broadly. Not only is the device new in its entirety, but we have combined certain elements less than the whole device which are new.

Our invention finds an important use in the art of extinguishing fires by the use of an extinguishing fluid such as CO₂ gas. One of the essentials of a releasing device for containers carrying CO₂ gas is that it be quick and positive in its operation so that the gas will positively be released in as quick a time as possible after the device is set into operation.

In our co-pending applications entitled Pressure-operated means for puncturing closure diaphragm, Serial No. 208,795, filed July 27, 1927; Device for puncturing closure disc, Serial No. 208,717, filed July 27, 1927; Closure release and combination for automatically closing a closing member, Serial No. 349,924, filed March 26, 1929; Manual cam-pull head for puncturing closure disc, Serial No. 336,156, filed Jan. 30, 1929; and Gas-operated screw type head for puncturing closure disc, Serial No. 336,157, filed Jan. 30, 1929, we illustrate different means for releasing a fluid from a container. In the present invention one of our objects is to provide a device in which the puncturing member is operated by a diaphragm.

It is also an object of the invention to provide a device in which the puncturing member after it punctures the closure disk is forced against a seat by the released fluid so that a seal is formed around the puncturing member and so that no fluid may escape around the puncturing member.

Another object of our invention is to provide a device in which the puncturing member is forced into puncturing position by a pressure which may continue for a period of

time, and in which the puncturing member has a sealing means for forming a sealing pressure while it is held in puncturing position so that no fluid may escape around it.

Other objects and advantages of the invention will be made evident hereinafter.

Referring to the drawings which are for illustrative purposes,

Fig. 1 is a vertical central section through a device embodying our invention, the parts being shown in normal position.

Fig. 2 is a transverse section taken on the line 2—2 of Fig. 1.

Fig. 3 is a view similar to Fig. 1, but showing the parts in actuated position.

Referring to the drawings, the numeral 11 designates a container for fluid under pressure. The container is provided at its neck with a threaded flange 12. A central projection 13 extends upwardly above the flange 12. This projection 13 is threaded to receive a cap 14 which holds a closure disk 15 in place. This closure disk 15 is adapted to close the outlet opening 16 of the container 11.

Our invention provides a body 18 having a lower face 19 adapted to be releasably held in engagement with the upper face of the flange 12 by means of a union member 20. The body 18 has an opening forming a chamber 21 which surrounds the projection 13. Connected to the upper part of the chamber 21 is a pipe 22 by which the fluid released from the container is carried to the place of use.

The upper part of the body 18 is provided with a radial flange 23 to which is secured a top or cover plate 24, the plate 24 being secured to the flange 23 by suitable cap screws 25. A chamber 26 is formed between the plate 24 and the upper end of the body 18. A flexible diaphragm 27 is mounted between the flange 23 and plate 24 to operate in the chamber 26. The diaphragm 27 may be flexed from the position shown in Fig. 1 into the position shown in Fig. 3 by admitting pressure into the chamber 26 above the diaphragm. This pressure may be admitted through a pipe 28, connected to the plate 24 and communicating to the chamber 26 by 100

an opening 30. The fluid admitted into the chamber 26 may be withdrawn from the chamber 26 by a pipe 31 connected with an opening 32 into the plate 24. The flange 23 below the diaphragm 27 is provided with vents 33 so that no pressure can be built up to oppose the pressure above the diaphragm. Connected to the central part of the diaphragm is a puncturing member 36. The connection of the puncturing member 36 to the diaphragm 27 is accomplished by a pair of nuts 37 which are screwed onto an end 38 of the puncturing member 36. The puncturing member extends downwardly from the diaphragm through an opening 39 in the wall of the body 18 which forms the top of the chamber 21. The opening 39 may be provided with a packing 40 of desired. The puncturing member has an enlarged portion 42 within the chamber 21, the upper end of which is provided with a conical valve face 43 adapted to engage a valve seat 44 provided around the inner or lower end of the opening 39. The engagement of the valve face 43 and the valve seat 44 forms a seal around the puncturing member to prevent leakage when the puncturing member is in normal position as shown in Fig. 1. The valve construction just described constitutes the secondary valve means of the invention.

The lower nut 37 engaging the diaphragm is provided with a valve face 46 which is adapted to engage a valve seat 47 which surrounds the upper end of the opening 39 when the puncturing member is in actuated position as shown in Fig. 3. The valve construction just described constitutes the primary valve means of the invention.

The lower end of the puncturing member 36 is cylindrical and extends into a cylindrical opening 47 provided in the cap 14 which holds the closure disk 15 in place.

The lower end of the puncturing member is provided with a knife edge 48 which adapts it for puncturing the closure disk 15. The puncturing member is provided with an opening 49 which extends upwardly from the lower end of the puncturing member and communicates with the opening 16 of the container when the closure disk 15 has been penetrated. The upper end of the opening 49 is connected by lateral openings 50 with the chamber 21 so that the fluid when released from the container 11 may flow into the chamber 21 and then through the pipe 22.

The operation of the invention is as follows:

The releasing device normally occupies the position shown in Fig. 1. When it is desired to release the fluid from the container 11, a pressure is created in the chamber 26 above the diaphragm 27. In the drawings we have illustrated pressure-creating means as pipes for conveying a fluid under pressure to the chamber 26 and from it. It should be under-

stood that other pressure-applying means may be provided such as an explosion device, as shown in our application for Letters Patent entitled Device for puncturing closure disc, Serial No. 208,717, filed July 27, 1927. When the pressure is created in the chamber 26 above the diaphragm 27, the diaphragm 27 is forced down into the position shown in Fig. 3 so that the primary valve means is closed, and so that the knife edge 48 of the puncturing member 36 has penetrated the closure member 15. At this time the fluid in the container 11 passes through the opening 16 thereof, the opening 49, the openings, 50, and into the chamber 21. As long as sufficient pressure is maintained in the upper part of the chamber 26 the puncturing means will occupy the position shown in Fig. 3.

With the parts thus positioned, none of the fluid in the chamber 21 can escape from the chamber around the puncturing member due to the fact that the primary valve is closed and forms a seal. This primary valve means is of particular value, where it is possible that the pressure in the chamber 26 may be of some duration. If an explosive means is utilized to maintain a pressure, this pressure is of short duration and the primary valve means is not as necessary.

When the pressure in the chamber 26 decreases so that there is sufficient differential between the pressure in the chamber 21 and that in the chamber 26, the puncturing member 36 will return to normal position, as shown in Fig. 1. At this time the secondary valve at the upper end of the chamber 21 will be closed so that at this time there is a seal provided around the lower end of the opening 39 which prevents a leakage of fluid around the puncturing member 36.

The important parts of the invention are the combination of a puncturing member and a diaphragm for operating the puncturing member. The primary and secondary valves also constitute an important part of the invention in that they form a seal for preventing leakage. The type of puncturing member which is provided is likewise important, since it is designed so that it will not obstruct the passage of fluid from the container 11 and so that the force of the stream of fluid is directed to push the puncturing member 36 upward. In this way the velocity of the fluid as well as its pressure is utilized to return the puncturing member to the position shown in Fig. 1.

We claim as our invention:

1. In a device for use in connection with a fluid container having an opening and a closure for said opening; a body having a chamber communicating with said opening; a puncturing member extending into said chamber and operable to open said closure; a diaphragm for operating said puncturing member; and means for applying a pressure

- against said diaphragm so as to operate said puncturing member.
2. In a device for use in connection with a fluid container having an opening and a closure for said opening; a body to be connected with the container at said opening; an axially movable puncturing member carried by the body and operable to open said closure; a diaphragm for operating said puncturing member; and means for applying a pressure against said diaphragm so as to operate said puncturing member.
3. In a device for use in connection with a fluid container having an opening and a closure for said opening; walls forming a chamber around said opening; a puncturing member extending into said chamber and operable to open said closure; a diaphragm for operating said puncturing member; means for applying a pressure against said diaphragm so as to operate said puncturing member; and sealing means for forming a seal around said puncturing means when said puncturing means is in operated position.
4. In a device for use in connection with a fluid container having an opening and a closure for said opening; a body forming a chamber around said opening; a puncturing member extending into said chamber and operable to open said closure; a diaphragm for operating said puncturing member; means for applying a pressure against said diaphragm so as to operate said puncturing member; and sealing means for forming a seal around said puncturing member when said puncturing member is in normal position.
5. In a device for use in connection with a fluid container having an opening and a closure for said opening; a body forming a chamber around said opening; a puncturing member extending into said chamber and operable to open said closure; a diaphragm for operating said puncturing member; means for applying a pressure against said diaphragm so as to operate said puncturing member; primary sealing means for forming a seal around said puncturing means when said puncturing means is in operated position; and secondary sealing means for forming a seal around said puncturing member when said puncturing member is in normal position.
6. In a device for use in connection with a fluid container having an opening and a closure for said opening; walls forming a chamber around said opening; a puncturing member extending into said chamber and operable to open said closure; a diaphragm for operating said puncturing member; means for applying a pressure against said diaphragm so as to operate said puncturing member; and sealing means for forming a seal around said puncturing means when said puncturing means is in operated position,
- said sealing means including a valve on said puncturing member adapted to engage a seat on said walls.
7. In a device for use in connection with a fluid container having an opening and a closure for said opening; walls forming a chamber around said opening; a puncturing member extending into said chamber and operable to open said closure; a diaphragm for operating said puncturing member; means for applying a pressure against said diaphragm so as to operate said puncturing member; and sealing means for forming a seal around said puncturing member when said puncturing member is in normal position, said sealing means including a valve on said puncturing member adapted to engage a seat on said walls.
8. In a device for use in connection with a fluid container having an opening and a closure for said opening; walls forming a chamber around said opening; a puncturing member extending into said chamber and operable to open said closure; a diaphragm for operating said puncturing member; means for applying a pressure against said diaphragm so as to operate said puncturing member; primary sealing means for forming a seal around said puncturing means when said puncturing means is in operated position; and secondary sealing means for forming a seal around said puncturing member when said puncturing member is in normal position, said secondary sealing means including a valve on said puncturing member adapted to engage a seat on said walls.
9. In a device for use in connection with a container having an opening and a closure for the opening; a body having a chamber, a punch extending into the chamber and operable to open the closure, and a fluid pressure actuated diaphragm for operating the punch, the punch having an opening for conducting fluid from the container to the chamber upon the closure being opened.
10. In a device for use in connection with a container having an opening and a closure for the opening, a body for connection with the container and having two spaced chambers, one for communication with said container opening and having an outlet, and the other for connection with pressure supply means, a punch extending between the chambers and operable to open the closure, and a diaphragm in the last-mentioned chamber for operating the punch.
11. In a device for use in connection with a container having an opening and a closure for the opening, a body for connection with the container and having two spaced chambers, one for communication with said container opening and having an outlet, and the other for connection with pressure supply means, a punch extending between the chambers and operable to open the closure, and a

diaphragm in the last-mentioned chamber for operating the punch, said last-mentioned chamber being vented at one side of the diaphragm.

- 5 12. In a device for use in connection with a container having an opening and a closure for the opening, a body for connection with the container and having two spaced chambers, one for communication with said container opening and having an outlet, and the other for connection with pressure supply means, a punch extending through the body between the chambers and operable to open the closure, sealing means around the punch where it passes through the body, and a diaphragm in the last-mentioned chamber for operating the punch.
- 10 15. In a device for use in connection with a container having an opening and a closure for the opening, a body for connection with the container and having two spaced chambers, one for communication with said container opening and having an outlet, and the other for connection with pressure supply means, a punch extending through the body between the chambers and operable to open the closure, sealing means around the punch where it passes through the body, and a diaphragm in the last-mentioned chamber for operating the punch.

In testimony whereof, we have hereunto set our hands at Los Angeles, California, this

20 24th day of January, 1929.

SCOTT E. ALLEN.
OZRO N. WISWELL.
